(57) **CLAIM**

The ornamental design for the "transition strip," as shown and described.

DESCRIPTION

FIG. 1 is a top perspective view of the transition strip, broken in the center for ease of illustration.

FIG. 2 is a bottom perspective view of the transition strip.

FIG. 3 is an end view of the transition strip taken from the left of FIG. 1.

FIG. 4 is a front elevational view of the transition strip of FIG. 1.

FIG. 5 is an end view of the transition strip taken from the right of FIG. 1.

FIG. 6 is a rear view of the transition strip of FIG. 1.

FIG. 7 is a top view of the transition strip of FIG. 1; and, FIG. 8 is a bottom view of the transition strip of FIG. 1.
